DAILY DUTY RECORD CHART

Martha J. Chick, 28026 Ormond Ave., Hayward, Calif.

Filed Apr. 15, 1963, Ser. No. 74,428

Term of patent 7 years

(Cl. D25—1)

FIG. 1.

The essential features of my design reside in the full line disclosure on the drawing.

I claim:

The ornamental design for a daily duty record chart, substantially as shown and described.
